Primary Examiner — Clint A Samuel**CLAIM**

The ornamental design for an astronaut shaped projection lamp as shown and described.

DESCRIPTION

FIG. 1 is a front perspective view of an astronaut shape projection lamp showing my new design;
 FIG. 2 is a front view thereof;
 FIG. 3 is a rear view thereof;
 FIG. 4 is a left side view thereof;
 FIG. 5 is a right side view thereof;
 FIG. 6 is a top view thereof;
 FIG. 7 is a bottom view thereof;
 FIG. 8 is a rear perspective view thereof; and,
 FIG. 9 is an enlarged detailed view of encircled area 9 in FIG. 1.

The broken lines encircling portions of the astronaut shape projection lamp in FIG. 1 and illustrated in enlarged views in FIG. 9 form no part of the claimed design.

The broken lines in the drawings depict portions of the astronaut shaped projection lamp that form no part of the claimed design.
